UNITED STATES PATENT OFFICE.

ARTHUR LUCKWEIL, OF MANNHEIM-NECKARAU, GERMANY.

ROPE BELT, ROPE BAND, AND THE LIKE.

1,106,658.

Specification of Letters Patent.

Patented Aug. 11, 1914.

Application filed September 5, 1911. Serial No. 647,587.

To all whom it may concern:

Be it known that I, ARTHUR LUCKWEIL, a subject of the German Emperor, and residing at Mannheim-Neckarau, in the German Empire, have invented certain new and useful Improvements in Rope Belts, Rope Bands, and the like, of which the following is a specification.

Rope belts, bands and the like composed 10 of ropes, consisted hitherto of separately formed ropes which ropes were connected together by a separate process to form the belt or the like. The connecting together of the ropes to form the belt 15 has been effected by means of wires passed transversely through the ropes and then riveted at their ends, or by means of stitching extending across or along the ropes. These methods of connecting the 20 ropes have the drawback that they take up much time and are therefore costly and are also wanting more or less in durability.

The present invention consists of a plurality of independent braids of rope or 25 strands united at their proximal edges by independent strands braided together and interlocking with said proximal edges. By this means a much stronger, uniform and durable belt is produced than with the proc- 30 esses above mentioned.

A further advantage is that such rope belts can be made very much more quickly and therefore cheaply and of superior quality and more durable.

35 The new belt has great advantages more particularly for hoisting machines, etc. Such belts which are usually composed of wire ropes are extremely difficult and therefore very expensive to manufacture accord- 40 ing to the old process. The new belt does away with the hand labor which was hitherto required for connecting together the wire ropes.

45 In the drawings: Figure 1 is a diagrammatic plan view of an apparatus for making rope belts according to this invention. Fig. 2 is a view of a braided belt embodying my invention, the connecting strands being 50 shown drawn out and apart for the sake of clearness.

The rope belt shown in Fig. 2 consists, for example, of two square ropes, which are connected together by special (auxiliary) strands *a* to *h*; these strands being interlaced in turn with the corresponding strands 55 of the two ropes.

Fig. 1 illustrates an apparatus for making rope belts and comprises two braiding machines. The braiding machine A comprises four bobbin carrier disks *A*¹ *A*² *A*³ and *A*⁴; the braiding machine B comprises four carrier disks *B*¹ *B*² *B*³ and *B*⁴. Each braiding machine A and B contains for instance eight strand bobbins so distributed and guided as to each produce one rope or 60 square cross section. Each braiding machine accordingly works independently and acts like a separate machine. The strand bobbins 1, 2, 3, 4 of machine A travel in the paths indicated by the single headed arrows, 65 while the bobbins 5, 6, 7, 8 travel in the paths indicated by the double-headed arrows. Similarly the bobbins, 1¹ 2¹ 3¹ 4¹ 5¹ 6¹ 7¹ and 8¹ of the braiding machine B travel in the paths indicated respectively 70 by the single headed and double-headed arrows. The bobbins may be distributed in other ways and a greater or less number may be employed for the purpose of producing another braiding. Similarly six or another 75 number of carrier disks may be employed in each machine for making a hexagonal, etc., rope. Special auxiliary strands are employed which may have the same thickness as the main strands but which may also 80 be thicker or thinner than these. Their bobbins are arranged and alternately guided in the machines A and B in such a manner that they travel first in one machine and then in the other machine so as to engage 85 with the corresponding strands of the ropes. Thus four bobbins *a*, *b*, *c*, *d*, are so arranged and are so guided that they travel in the path indicated by the circle-tailed arrows, 90 that is to say, they travel first with the disk *A*² of the machine A, then over the disk *B*³ to the disk *B*² of machine B, and thence over the disk *A*⁴ back again to machine A 95 and disk *A*².

Four other bobbins *e*, *f*, *g*, *h*, travel at the 100 same time along the path indicated by cross tailed arrows, namely over the disk *B*³ of machine B, then over the disk *A*² to disk *A*⁴ of machine A, thence over disk *B*² back again to machine B and disk *B*³. The paths 105 of these two kinds of bobbins thus cross one another again so that the respective strands are also braided together. In this process, the auxiliary strands are interlaced with the rope strands in the following order: *a* with 110 1; *b* with 2; *c* with 3; *d* with 4; then *a* with 1¹; *b* with 2¹; *c* with 3¹; *d* with 4¹; and at

the same time *e* is interlaced with *5¹*; *f* with *6¹*; *g* with *7¹*; *h* with *8¹*; then *e* with *5*; *f* with *6*; *g* with *7*; and *h* with *8*.

What I claim as new and desire to secure
5 by Letters Patent is:—

A braided belt consisting of a plurality of
braids each made of strands independent of
the strands of the other braid, said braids
being united at their proximal edges by in-

dependent strands braided together and in- 10
terlocking with said proximal edges.

In testimony whereof I affix my signature
in presence of two witnesses.

ARTHUR LUCKWEIL.
